UNITED STATES PATENT OFFICE.

JOSEPH ARTHUR BOUCHER, OF MONTREAL, QUEBEC, CANADA.

RECEIPT-FORM.

1,383,596.

Specification of Letters Patent.

Patented July 5, 1921.

Application filed December 10, 1918. Serial No. 266,086.

To all whom it may concern:

Be it known that I, JOSEPH ARTHUR BOUCHER, a subject of the King of Great Britain, and resident of the city of Montreal, in the Province of Quebec, Dominion of Canada, have invented new and useful Improvements in Receipt-Forms, of which the following is a specification.

This invention relates to improvements in contract forms, especially for contracts involving a number of consecutive, serial payments such, for example, as the contracts written by industrial insurance companies, and the objects of the invention are to facilitate the collection of the payments, to prevent error, to save time in making the collection and to avoid fraud on the part of the collector.

Further objects are to insure that no money be collected without an official receipt being given. Further objects still are to reduce the amount of bookkeeping necessary, to enable the contract form itself to constitute a complete record of the transaction, giving the exact standing at any particular period, in such a form as to constitute such legal proof as will be indisputable. The invention consists essentially of the improved form hereinafter described in detail in the accompanying specification and drawings.

In the drawings:

Figure 1 is a plan view of the face of the form embodying the invention.

Fig. 2 is a detail in plan of a portion of the back of the form illustrated in Fig. 1.

In the drawings like characters of reference indicate corresponding parts in all the figures.

By reference to the drawings it will be seen that the form comprises a sheet ruled to provide a series of detachable coupons A, which may be separated from each other by perforations or weakened lines so that they may be readily detached. In addition to the coupons a space B is provided in which the principal terms of the contract may be printed. The coupons correspond in number to the number of serial payments to be

made under the contract and will be numbered consecutively. They also bear on their face the amount of the payment and the date that it is to be made; on the back of each coupon is marked the year of the payment and the number of the coupon in the series, that is to say, whether the pay-

ment is for the first week, the second week or so on.

The form is further provided by ruling, with a plurality of checking spaces C which are in number the same as the number of coupons, and are numbered to correspond with the serial number of the coupon, this being designed to receive the inspector's initials or checking mark. A further space D may also be provided to contain particulars as to the collector, checker, cashier, district number, etc.

The form *per se* does not constitute a contract but is used in the collection of payments, etc., to be made in the fulfilment of a contract. Each form is identified by having printed or otherwise shown thereon some of the terms of the contract, and in the embodiment illustrated it will show the contracting parties, the nature of the contract, the payments to be made and when due, the checking system, etc.

It will be understood that the contract proper, which has nothing to do with the present invention may have certain other terms which would not be disclosed in the form which constitutes the present invention, because such terms would not have any bearing on the collection of the dues or the checking, etc., of such dues.

By way of illustration the form has been shown as for a policy in "Boucher's Industrial Insurance Co., Ltd., " twenty year endowments, one hundred dollar policy having a weekly premium of ten cents, the policy being issued Dec. 12, 1901, and being due Dec. 12, 1921; these particulars with the number of the policy being printed in the space B. The sheet is shown as having twenty-six coupons which will serve for one-half year's payments, each coupon being marked on the back with the year and as to the number of the week or payment in the series, thereby the period covered by the contract is indicated in the space D, that is to say, the weekly payments to cover from Jan. 6 to June 30, inclusive, the exact date of the payment being indicated on the coupon itself.

In using the form for the purpose illustrated the treasurer of the insurance company will issue each year a number of receipts to be collected at different dates during the year. They may be weekly or monthly payments. These sheets will be distributed to different sections and charged to

to the same. These sections will then deliver the forms to the district agents who pass them to the local collectors, the treasurer thus issuing millions of forms all different. 5 The collector when being paid an instalment of the dues will detach a particular coupon forming a receipt for that particular payment, and he will exchange this coupon at the insured's house for the fee, which 10 will be returned to the head office by the same channel in which the receipt forms are issued.

Any unpaid premium will leave the coupon attached to its form which will be returned in due course to the head office. When 15 a coupon is detached from the contract form then it signifies that the payment corresponding to such coupon has been made, and this is a sufficient valid receipt, although at 20 the same time the coupon in the hands of the insured person would also form a receipt, so that there is a double checking of the mon- 25 eys paid in connection with any particular policy.

25 Should any receipt be lost it may be replaced by a special receipt, which would have all the characteristics of the ordinary coupon and would only differ therefrom, by the collector indicating the reason why he 30 issued the special receipt. If any errors occur in distributing receipts, it would be very easy to trace them, as the right receipt will be at its place on the sheet if another has been delivered by accident. It will be ob- 35 served that in this manner of making collection considerable time and work will be saved as no writing will be done by the collector; the collector having received the premium will preferably enter the same in a 40 suitable "Bordereau" with attached receipt coupon to be returned to the collector. A numbered receipt book will also be preferably kept by the insured, made of gum paper, having numbered spaces corresponding to the serial numbers on the coupons upon 45 which the coupons may be stuck and which will thus indicate to him that the payments have been made regularly without omission.

50 It will be seen that this system avoids the error of entries made by the collectors or in the insured's receipt book. It is also impossible for the collector to collect advance fees without the inspector or checker noting it by the absence of receipts on the sheet.

55 The collectors make their returns to the dis-

trict agents at predetermined intervals, and the forms of each contract would then be checked up, and the inspector would initial the particular space in the column C, which directly refers to a particular coupon A, 60 the inspector could also mark in the column C any remarks which he desires to make, so that when forms are being returned by a collector an immediate checking of the several forms is made, and in this way irregularity 65 in any contract form would immediately be noticed.

As many changes could be made in the above construction and many apparently widely different embodiments of my invention within the scope of the claim, constructed without departing from the spirit or scope thereof, it is intended that all matter contained in the accompanying specification and drawings shall be interpreted as illustrative and not in a limiting sense. 75

What I claim as my invention is:

A contract form designed to cover a contract and calling for a number of serial payments comprising a sheet ruled with horizontal and vertical lines to provide a series of coupons on its face, the said coupons extending to one side and one bottom of the face, and having printed on the back thereof the numerical order of the serial payment, each coupon further having printed on the face thereof the amount of the payment and the serial number of the contract; a space B above the coupon in which the terms and serial number of a contract are 80 printed; and a series of numbered rectangular checking spaces C immediately to one side of the coupons, each of the numbers on the checking spaces corresponding with one 85 number of the numerated payments printed on the back of the coupons, each form further having a space E bounded by the rectangular checking spaces, the coupons and the space B and having printed thereon particulars as to the serial number of the contract, division of the territory for the distribution 90 of the forms, cashier, collector, checker, and a space D above the rectangular checking 95 space C and adjacent to the space B, having particulars as to the number of receipts 100 and the number of the sheet of the contract imprinted therein.

In witness whereof I have hereunto set my hand.

JOSEPH ARTHUR BOUCHER.
